UNITED STATES PATENT OFFICE.

WILLIAM J. FELTON, OF ANNISTON, ALABAMA.

SMOKING-PIPE.

No. 800,730.

Specification of Letters Patent.

Patented Oct. 3, 1905.

Application filed June 13, 1904. Renewed August 2, 1905. Serial No. 272,336.

To all whom it may concern:

Be it known that I, WILLIAM J. FELTON, a citizen of the United States, residing at Anniston, in the county of Calhoun and State of Alabama, have invented certain new and useful Improvements in Smoking-Pipes, of which the following is a specification.

This invention relates to improvements in smoking-pipes; and the especial object of the 10 improvements is to provide a pipe which will take the nicotine from the tobacco-smoke in its passage from the bowl to the stem.

A further object is to provide a pipe having the above-named object which can be cheaply 15 made and in which the parts are all accessible for cleaning purposes and can be taken apart and readily renewed in whole or in part.

In the accompanying drawings, which form a part of this application, Figure 1 represents 20 a vertical section taken through a pipe made in accordance with my invention and a longitudinal section through the stem attached to said pipe. Fig. 2 is a perspective view of the tobacco-holding bowl of my improved pipe, 25 and Fig. 3 is a perspective view of the cap or closure for the bottom of the pipe bowl or shell.

Referring to the drawings in detail, *a* represents the outer shell of my improved pipe, 30 which is cylindrical in form, is open at the top and bottom, and is threaded on its inner wall near the bottom to receive the cap *c*, provided with external threads *c'*, which are adapted to engage the corresponding female threads in 35 the shell, thus forming a removable closure for the lower end of the shell. Fitting snugly within the shell is a cylindrical bowl *b*, which is adapted to hold the tobacco, is formed with an opening *b'* through its bottom, and on its 40 external face is provided on opposite sides with vertical grooves *b''* and with an annular groove *b'''*, with which the upper ends of the vertical grooves *b''* communicate. The vertical diameter of the bowl *b* is somewhat less than the corresponding diameter of the shell, so that when 45 the bowl is in position a space will be left between the bottom of the bowl and the upper side of the cap *c*. This space is adapted to be filled with any suitable fibrous absorbent or filtering 50 medium, as *d*, which will act as a filter for the smoke and catch the nicotine contained in such smoke. Extending across the bottom of the bowl is a slight recess into which is fitted the upper edge of the vertical rib *c'*, which is 55 formed integrally with the cap and extends across the upper face of the same, as shown

in Fig. 3. This vertical rib forms a partition which extends transversely of the chamber in which the filtering medium *d* is placed and is so arranged that it will be opposite the inner end 60 of the stem *a'* of the pipe, which is of the usual form and provided with a mouthpiece *a''*. The stem is connected with the bowl in any suitable manner and is provided with the usual smoke-passage.

The bowl *b* is fitted into the shell preferably by close frictional contact between the adjacent walls of said parts, so that with the exception of the grooves *b''* *b''* *b'''* there will be no smoke-passage between the outer wall of 70 the bowl and the inner wall of the shell, whereby the smoker in drawing on the stem will draw the smoke down through the opening *b'*, the filtering medium *d*, up one of the 75 passages *b''*, around the annular passage *b'''* until it reaches the opposite vertical groove *b''*, from which it will be drawn down to and through the stem of the pipe, and thus reach the smoker's mouth.

It will be apparent that in traversing the 80 circuitous passage above indicated and the filtering medium the smoke will be necessarily relieved of the major part of its nicotine before it reaches the smoker's mouth. It will also be apparent that if it be desired to clean 85 the portions of the pipe exposed to the smoke it will be necessary only to unscrew the cap *c*, remove the filtering medium *d*, push out the bowl *b*, wipe out the inner wall of the shell *a* and the outer wall and grooves of the 90 bowl. The upper face of the cap *c*, including its rib *c'* and the stem smoke-passage, may be cleaned in a similar manner.

I do not limit myself to any particular material of which the shell and the bowl may be 95 composed, nor to any particular form or shape of said parts, nor to any special number of vertical or annular grooves, as I may wish to modify the construction in these respects without altering the essential principles or changing the function of my improved pipe.

Having thus described my invention, what I claim as new, and desire to obtain by Letters Patent, is—

1. In a pipe, a shell, a removable closure for the bottom of the shell, a bowl adapted to be inserted within the shell and to leave a chamber in the lower portion of the shell, said bowl provided with an opening in its bottom communicating with said chamber, and said shell provided with a partition extend-

ing across said chamber and secured to the removable closure, a stem communicating with the chamber on one side of said partition, and smoke-passages connecting said

5 chamber with the smoke-passage in said stem.

2. In a pipe, a shell provided with a stem and with a removable closure, a bowl adapted to fit within said shell and to have a chamber in the lower portion of the shell, a partition formed integrally with said closure and extending across said chamber, and smoke-passages extending from the interior of the bowl

on one side of said partition, through said chamber, and around the outside of said bowl, and communicating with the smoke-passage 15 in said stem on the opposite side of said partition.

In testimony whereof I affix my signature in presence of witnesses.

WILLIAM J. FELTON.
